ARCH AND WALL CONSTRUCTION

Paul Wright, Birmingham, Ala.

Application March 9, 1944, Serial No. 525,772

19 Claims. (Cl. 110—99)

1

This invention relates to arch and wall constructions, used for furnaces and for structures that are subjected to the action of heat.

This application constitutes a continuation in part of my application filed September 12, 1939, Serial No. 294,568 for Arch and wall, now Patent 2,346,638, April 11, 1944.

An object of this invention, is to provide an arch or wall structure that is externally heated, whereby the temperatures of the structure itself, are varied by heat absorption means within the structure.

A further object is to provide an arch or wall structure that is constructed, in part, with plastic or castable material that is molded in place, whereby said material incases a cushioning insulation that surrounds tube elements which are arranged within the structure.

Another object is to provide a structure that is constructed with spaced tube elements arranged within said structure, said tube elements being surrounded with a cushioning insulation, which insulation is incased by firm blocks, which blocks hold plastic or castable material constructed there-between.

My invention further contemplates the provision of a composite wall construction with spaced tube elements, either in the form of separate tubes or as spaced coils of a single tube; and cooperating pairs of tube blocks incasing said tube elements which are surrounded with cushioning insulation interposed between said blocks and tube elements; moldable plastic or castable material occupying the space between the blocks on adjacent tube elements, whereby said blocks and moldable material form the refractory portion of said wall; and a back-up layer of hollow tile or brick masonry, that is retained in contact with said refractory portion by means of fasteners secured to said tube elements.

A still further object, is to provide a wall structure, which employs within it, tube elements shaped as a helix or as a spiral, thereby enabling the interior surface of said wall to be shaped to a contour.

In this description and the appended claims, the term "tube elements" is intended to cover separate tubes, or separate coils of a single coiled tube.

The various features of novelty which characterize my invention are pointed out with particularity in the claims annexed to and forming a part of this specification. For a better understanding of the invention, its operating advantages and specific objects attained by its use,

reference should be had to the accompanying drawings and description in which I have illustrated and described preferred embodiments of the invention.

5 Of the drawings:

Fig. 1 is a cross-section of a structure utilizing moldable materials, as illustrating an irregular shaped arch of my invention, whose tube elements are approximately parallel, yet said tube elements may be straight or curved.

Fig. 2 is a horizontal section of a structure partially made of moldable material, the view being taken on lines 2—2—2 of Fig. 3.

Fig. 3 is a vertical section and elevation view 15 of Fig. 2 taken on lines 3—3—3.

Fig. 4 is a plan view of part of a curved structure that embodies the invention.

Fig. 5 is a section on line 5—5 of Fig. 4, showing one form of the structure as made with its 20 tube elements in helical form.

Fig. 6 is a section of a quadrant as taken on line 5—5 of Fig. 4, but utilizing plastic or castable materials that are molded in place.

Fig. 7 is a composite plan of a flat structure 25 embodying the invention and it provides tube elements in the form of spiral coils, the views being partial top and sectional plans as taken on lines 1—1 of Fig. 8.

Fig. 8 is a transverse sectional view of the structure of Fig. 7 as taken on lines 8—8, showing one arrangement of the spiral tube coils.

Fig. 9 shows composite views of a structure embodying the invention as having a conical shaped wall constructed with spiral tube coils, 35 the views being a partial outer elevation shown in relation to the partial sectional elevation.

Fig. 10 is a sectional view of a spiral tube coil shown in its relation to the cushioning material and molded material, as taken on section 10—10 40 of Figs. 7 and 9.

In the structure, embodying my invention illustrated in Fig. 1, spaced tube elements 1 serve as structural members that are surrounded by a cushioning insulating material 2. This insulation 2 may be preformed, as for example as partial cylinders of any suitable materials having cushioning properties, such as, expanded mica compounded with a binder, asbestos fiber compounded, fiber glass, or mineral wool. Such preformed cushioning insulation is temporarily held 45 about the tube element with tie strings or wires 3 that wrap as construction ties, preparatory to placing the moldable material 4. Other forms of insulation 2, such as a tape that is wrapped 50 around the tube element, can be used, since the

55

insulation is not limited by any practical substance that can serve as an insulating or cushioning material.

As an example, plastic refractory 4 is placed about the insulated cushioned tube elements as shown by Fig. 1. A severed parting or joint 5 facilitates placing the refractory in sections. This joint 5 also provides for expansion and contraction between the portions 4, since the cushioning material yields to expansive movement of portions 4, both transversely and longitudinally about tube elements 1. This feature reduces cracking of the structure after it has been cured or burned in service. The tube elements may be flexibly held, and as one example, they may be arranged one horizontal tube element above another adjacent element, as in a wall.

An important feature of the insulation 2, is that it facilitates curing or suitably heating plastic 4 to give it a more rigid form. Thus tube element 1 is protected against overheating, since excessive heating could be detrimental to the tube element. And, since a cooling medium is at times employed within tube elements 1, obviously insulation 2 shields the contacting plastic 4 against giving up its heat to the tube element 1; whereby the portion of plastic near the tube elements can absorb heat, or, the insulation prevents cooling from the tube element, to a degree that would prevent a "set-up" of the plastic adjacent the tube elements.

This construction of Fig. 1 advantageously accommodates an arranged spacing of the tube elements 1, whereby the outer surfaces of an arch may be made with plane sides or with sides curved, as may effect an economy of the materials and also suit special heat reflecting properties related to radiation, of the arch.

The structure of Fig. 1 can be used as an arch arranged in any position, as for example, the roof of a furnace, a baffle arch within a furnace, or as a partition or wall within the furnace. The shape of the joints 5 can be arranged in a manner convenient for construction and to relieve the stresses due to expansion caused by heating of parts 4. The tube elements 1 may be straight or curved, and in either form the elements are approximately parallel.

Another important feature of the invention is gained by utilizing a tube covering 2 of a character that has insulating properties, since my construction facilitates the scope or degree of insulation that can be used about the tube, whereby the rate of heat absorption by a cooling medium within the tube element, can be varied. Furthermore, with a proper thickness of insulation 2 and the degree of its insulating value being made suitable, the average temperature within the Fig. 1 structure can be varied by a change in flow of a cooling medium thru the tube elements 1.

One practical advantage of the invention resides in the construction of a furnace which has walls and roof of Fig. 1, whereby the temperature of the atmosphere within the furnace can be influenced by the variation of the furnace wall temperatures, which are varied independently of the heat input into the furnace. Heretofore it has been customary to endeavor to control temperatures of a furnace's atmosphere, by a regulation of the heat input, as by control of fuel or delivery of heat in varied quantities into the atmosphere of the furnace itself. My invention provides a new feature, that the atmosphere of the furnace can be varied by a cooling medium within the wall as of Fig. 1, independently of the charge

or material to be heated, as for example within a heat treating furnace, also independently of the firing of the furnace. Conversely, a heating medium may be employed within the tube elements, as a means effecting changes of wall temperature, as for example in utilizing steam.

In utilizing plastic materials, it is customary to pack same into place, by applying portions that gradually adhere to build up the thickness required. This thickness is usually limited to a range of heat penetration that will cure or solidify and make a firm structure of the entire plastic.

Whereas Fig. 1 and the other drawings, show cylindrical tube elements, the invention is not limited to the shape of the tube element, acting as a support and as a conveyor of a fluid medium.

But my invention is not limited to plastic materials, since castable materials are practical. Castable refractory, for example, is poured in place and thereafter sets up in a solid form, without the necessity of applying heat for curing it, as is required for plastic. Also castables customarily do not have as high a heat range permissible as for plastics and my invention enables the control of the wall temperatures of castable material so as to facilitate its use. I classify both plastic and castable refractories, as being moldable refractory materials.

In Figs. 2 and 3, the construction of Fig. 1 is modified by using firm blocks that surround the cushioned tube element. Tube elements 1 of Figs. 2 and 3, are insulated and cushioned by a material 7 that is interposed between the tube element 1 and blocks 8 that are recessed as shown. As one example of my invention, the blocks 8 are shaped as shown by Figs. 2 and 3 so as to practically surround material 7, which cushioning may not be so firm as the preformed material 2 of Fig. 1. This permits pounding the plastic 4 like that in Fig. 1, into its place of Fig. 2 without distorting the cushioning 7 which is protected by refractory blocks 8 that are previously kiln burned and suitable to withstand handling and suitable to retard passage of heat thru same. As a means of providing a cheap but entirely practical cushioning 7, I can use granulated mineral wool as the material 7 of Figs. 2 and 3, also I can quickly pack it hand-tight into the recess of the blocks 8, as set about the tube element 1. Also an improvement resides in first using the annular washer or stop 6 that surrounds the tube element 1, just above the lower blocks 8 or at the bottom of the recess of blocks 8 that are to be filled with granular mineral wool 7, from above. Also this washer 6 may be a cement that is buttered on the blocks 8 as they are placed about the tube element 1, which cement 6 sets so as to resist packing of the granular material 7 into the recess beyond and beneath. Thus the blocks 8 may be centered around tube element 1 by means of stop 6 described, and any suitable material that will resist heat of the installation, can be used.

Probably less skill is required to build the construction of Figs. 2 and 3 than of Fig. 1; but I do show an outer closure 10 in Fig. 2, which closure can be an insulating board, used to back up the moldable material 4. Also in lieu of the board 10, a common tile or brick masonry wall could be used.

The features claimed for the wall of Fig. 1, are equally advantageous for the wall of Fig. 2, as regards the advantage of uniformly curing or heating the plastic refractory as held by blocks 8 and, said refractory 4 can be shaped as shown by Fig. 2 so as to save in its thickness or to provide an irregular or curved reflecting inner surface next to

the fire. Likewise the constructions of Figs. 4, 5 and 6 provide a similar curved reflecting inner surface next to the fire. I do not limit blocks 8 to the specific shape of Figs. 2 and 3, since their shape or contour may be varied so as to suitably contact and engage the said moldable materials 4, held in place by said blocks. The material of blocks 8 of Figs. 2 and 3, also the blocks 8c of Figs. 4 and 5, is not limited to kiln processed refractory, since other firm materials in block form serve for the invention.

The construction of Figs. 2 and 3 enables using blocks 8 that may vary some from their intended manufactured size, yet the finished construction is true to specified outer shape and it is arranged so as to provide for expansion and contraction, in the manner of Fig. 1 constructions.

Arches and walls that endure severe service should be repairable quickly, so save outage time and expense. The construction of Figs. 1, 2, and 3 permits tearing out parts of the plastic or castable 4, without necessarily damaging the insulation 2 and particularly is this an advantage of the Figs. 2 and 3 structures that employ firm blocks 8 to protect and shield the cushioning 7 surrounding the tube element 1. In Figs. 2 and 3, the use of blocks 8 with tube elements 1 can be employed with any suitable cushioning or insulating materials which were described as being usable for Fig. 1 constructions. The blocks 8 are separated by an appropriate expansion joint 5 that is similar to the joint 5 of Fig. 1. The blocks 8 can be temporarily held with tie wires 3 or string, wound around same and if need be, the joint 5 can be maintained parted during construction by a thin spacer of paper board or any suitable resilient substance 9.

By Figs. 1, 2 and 3, I have shown that the tube elements 1, act as structural members, about which the arch or wall is constructed and sustained. In various positions, the tube elements 1 act as supporting members or as binders for the arch or wall and such binder tube elements usually must be stiff or resistant to flexure. In some arches and walls of this invention, I use tubes without circulating a cooling medium through same. In others where a cooling medium is used, I prefer to employ air, gas, oil, steam or water, in various structures and I therefore use the term "cooling medium" as a general description for any of these. But I do not limit the kind of cooling medium to those named, since there are other heat absorbing substances that are usable as a cooling medium, also suitable to my invention.

The constructions of Figs. 4, 5 and 6 are like Figs. 2, 3 and 1 respectively, and curved tube elements 1c are used and the cushioning insulation 2c is shaped to fit. Likewise in Figs. 4 and 5, blocks 8c are provided with curved recesses that suit the tube element 1c as cushioned and insulated. The helical tube element 1c advantageously serves as a binding ring or retainer for the associated parts 2c and 8c, functioning somewhat like a hoop. The shape of blocks 8c may be varied so as to suitably contact and engage, the moldable materials 4c, as held in place by said blocks 8c.

Thus a hollow cylindrical structure of Fig. 4 can be used as a round furnace chamber. Such a furnace chamber can be arranged or positioned with the axis of its cylinder in various positions, since the curved tube elements 1c hold the assembled parts 1c and 8c and 4c in sustained form.

Where the tube elements of Fig. 1 are curved

and the elements are approximately parallel, the construction is similar to that of Figs. 4 and 6. Furthermore, the structures of Figs. 4, 5 and 6 readily accommodate expansions of the parts comprising same, as are caused by their being heated. For example if tube elements 1c are maintained at approximately uniform temperature, the parts 8c and 4c that absorb heat, may expand independently of tube elements 1c since the joints 5c and the cushioning materials 2c or 7c provide for expansive movement. The preformed material 2 of Fig. 1 and 2c of Fig. 6, is usable with the blocks 8 of Fig. 2 and 8c of Fig. 5, as the invention is not limited to such combinations. Furthermore, the joints of Fig. 5 between blocks 8c and Fig. 6 between portions of 4c material, such are contact joints without an intervening space between portions as for joint 5c of Fig. 4.

Another use of tube elements shaped in spiral form, provides for constructing furnaces that have an approximately conical inner surface or a surface that is shaped to a contour. Also the axis of the spiral tube elements may lie in approximately a plane, so as to provide a flat structure, utilizing the cushioning insulation and moldable refractory. For example, the construction of Figs. 7 and 8, employs spiral tube coils that lie approximately in a plane and the construction of Fig. 9 employs spiral tube coils as suiting a wall whose surface approximates a conical contour. The upper view of the tube coils 1s of Fig. 9 is similar to the view of tube coils 1s in Fig. 7. Fig. 10 shows for example preformed cushioning insulation 2s about coil 1s and providing an open joint 5s between moldable material 4s on the one side and the opposite side has the joint filled with a resilient substance 9s. In the several figures, like numerals represent like materials.

My invention provides arch and wall constructions whose exposed surfaces will withstand fire on both sides; also it provides a structure that may be internally heated or cooled by a medium passed thru its tube elements, whereby the stresses due to expansive movements of its structural parts are relieved.

While in accordance with the provisions of the statutes I have illustrated and described herein the best forms of the invention now known to me, those skilled in the art will understand that changes may be made in the form of the constructions disclosed without departing from the spirit of the invention covered by my claims, and that certain features of my invention may sometimes be used to advantage without a corresponding use of other features.

I claim:

1. A wall structure comprised of a plurality of substantially parallel tube elements, a layer of cushioning insulation in contact with and surrounding each of said tube elements; solid molded refractory sections, between and in contact around said cushioned insulated tube elements, each section substantially abutting adjacent the cushioning insulation.

2. An imperforate structure subjected to the action of heat, said structure comprised of a row of substantially parallel tube elements, a layer of preformed cushioning material provided in sections as substantially surrounding each tube element; and means comprising solid moldable material in sections between and contactual around said cushioned tube elements thus providing expansion joints between said sections,

said joints being transversely and longitudinally adjacent the tube elements of said structure.

3. A heat resisting structure subjected externally to fire, said structure comprised of a plurality of spaced tube elements flexibly held as enabling the expansion and contraction of said structure; a layer of cushioning material in contact with and surrounding each of said tube elements; a plurality of spaced rows of blocks, each of said rows including pairs of contacting blocks provided with recesses and substantially surrounding one of said cushioned tube elements and means to bind said blocks in place; and means comprising sections of moldable material inwardly and outwardly between and contactually around said rows of blocks, and abutting joints between sections.

4. In a structure of the character described, a plurality of spaced substantially parallel tube elements, a layer of interposed insulating material held in contact with and surrounding each of said tube elements by means of co-operating pairs of incasing tube blocks, and each of said blocks having a recess therein partially embracing its associated insulated tube element; means to bind said pairs of incasing blocks about the insulated tube elements, and solid moldable material in sections extending between and contactually around the said pairs of incasing blocks and with provision of expansion joints therebetween, adjacent the joints between said pairs of blocks.

5. A structure comprising a plurality of substantially parallel tube elements, a layer of cushioning material in contact with and surrounding each of said tube elements; a plurality of spaced rows of blocks each of said rows including pairs of contacting blocks provided with recesses and surrounding one of said cushioned tube elements; and molded material provided between the blocks in one of said rows and the blocks in an adjacent row, to hold said blocks in place on said cushioned tube elements, the assembled structure being imperforate.

6. In a structure of the character described, a plurality of spaced substantially parallel tube elements, co-operating pairs of tube blocks incasing said tube elements, each block having a recess therein partially embracing its associated tube element, cushioning material interposed between the blocks and the tube elements; and molded refractory material solidly contactual between said blocks on adjacent tube elements, whereby said cushioning material is protected by its incasing blocks.

7. A structure of the character described that comprises in combination, a tube element substantially helical in form, a layer of cushioning material in contact with and surrounding said tube element; co-operating pairs of tube blocks incasing said tube element, each block having a recess therein partially embracing its associated portion of the cushioned tube element; and material in sections that extend around and between said blocks.

8. In arch and wall construction of the character described, fixedly spaced substantially parallel tubes, co-operating parts of cushioning insulators, each insulator part having a recess therein partially embracing its associated tube and ties to hold the parts of said insulators to surround said tube; and means comprising solid molded material, in portions that extend inwardly and outwardly between and contactually around each of the said insulated tubes, and resilient partings

between said portions, with the partings adjacent the insulators.

9. In a furnace, a structure that comprises a plurality of substantially parallel tubes, a layer of insulation in contact with and surrounding each of said tubes; a plurality of spaced rows of blocks, each of said rows including pairs of contacting blocks provided with recesses and substantially surrounding one of said insulated tubes and means to bind said blocks in place; and plastic refractory between each of said rows of blocks.

10. In a structure of the character described, a row of spaced substantially parallel tubes, co-operating pairs of tube blocks incasing said tubes, each block having a recess therein partially embracing its associated tube and said blocks positioned about said tube with annular washers and cushioning material interposed between the blocks and tubes; means to bind said blocks in place, and moldable material between and substantially surrounding said blocks, the assembled structure forming a wall whose moldable material is repairable.

11. In arch and wall construction of the character described, a plurality of substantially parallel tubes, a layer of cushioning material held in contact with and surrounding each of said tubes; a plurality of spaced rows of blocks each of said rows including pairs of contacting blocks provided with recesses and substantially surrounding one of said tubes; ties to bind said blocks in place; and moldable material between and substantially surrounding said blocks and said moldable material provided with joints adjacent the joints between said blocks.

12. In a wall whose interior surface approximates a contour, approximately parallel tube elements arranged in pairs and a layer of cushioning material in contact with and surrounding each of said tube elements; and solid moldable material in sections extending inwardly and outwardly between and contactual around said cushioned tube elements, thus bounding the interior and exterior surfaces of said wall, and the moldable material divided by parting joints adjacent the cushioning material.

13. A flat structure comprised of a spiral tube element, a layer of cushioning material in contact with and surrounding said spiral and molded material in sections extending solidly between and contactually around the coils of said cushioned spiral tube element, and abutting joints between sections.

14. In a wall whose interior surface approximates a conical contour, a spiral tube element provided with a layer of cushioning material in contact with and surrounding the tube element of said spiral; and molded material in solid sections between and contactually surrounding the coils of said cushioned spiral, thus bounding the interior and exterior surfaces of said wall, and abutting joints between sections.

15. A structure subjected to the action of heat, comprised of tube elements providing means of heat transfer, through a layer of cushioning material in contact with and surrounding each of said tube elements, and molded material in contacting portions solidly between and substantially surrounding said adjacent cushioned tube elements, with abutting joints between portions.

16. A structure subjected to the action of heat, comprised of tube elements providing means of heat transfer, a layer of cushioning material in contact with and surrounding each of said tube elements, a plurality of spaced rows of blocks

each of said rows comprising pairs of cast blocks with recesses and surrounding in contact one of said cushioned tube elements, means binding said cast blocks about said cushioned tube elements; and molded material in sections that inwardly and outwardly are solid between, and contactual around said rows of blocks, and abutting joints between sections.

17. A structure subjected to the action of heat, said structure comprising a plurality of spaced tube elements suitable for conveying a medium transmitting heat; a layer of cushioning material yieldingly surrounding and contacting each of said tube elements; and rigid material constructed between and solidly surrounding in sections each cushioned tube element, and parting joints between said rigid sections, suitable for accommodating expansion.

18. A wall of the character described comprised of, a plurality of spaced tube elements, a layer of contacting cushioning material surrounding each of said tube elements; and means comprising solid moldable material in sections inwardly between and contactually surrounding each of the cushioned tube elements, and a back-up closure for said wall, outwardly against which said material bears, with abutting joints between sections.

19. In arch and wall construction of the character described, a tube element suitable for temperature changes, a layer of contacting insulation suitable for said temperature changes and yieldingly surrounding and contacting said tube

5

element; and sections of rigid material substantially surrounding and contacting said insulated tube element, with parting joints transversely and longitudinally adjacent the insulated tube element.
